UNITED STATES PATENT OFFICE

2,452,016

SMOKEHOUSE FOR FISH AND OTHER FOODSTUFF

Alfred L. Lyon, Eastport, Maine; Zelma A. Lyon, Roscoe C. Emery, and Charles C. Norton, all of Eastport, Maine, executors of said Alfred L. Lyon, assignors to Zelma A. Lyon, Roscoe C. Emery, and Charles C. Norton, all of Eastport, Maine, cotrustees.

Application November 27, 1943, Serial No. 511,976

6 Claims. (Cl. 99—259)

1

The present invention relates to an apparatus for curing by smoking fish and other food and is particularly concerned with obtaining a clean, sanitary product free from ashes and embers from the burning wood. This is accomplished by preventing the articles from coming in direct contact with the rising combustion resulting from the fire nearest the same, thereby obtaining a smoked article of the highest quality.

In order to obtain this result a specially constructed smoke house has been devised as illustrated in the accompanying drawings, in which:

Figure 1 represents a vertical section of the smoke house with the front wall removed, showing an upper and a lower floor thereof.

Figure 2 is a vertical section along the line 2—2 of Figure 3 of the oven with the fireplace, represented by a metal cylinder in elevation, and

Figure 3 is a horizontal section along the line 3—3 of Figure 2.

In the figures similar reference numerals indicate the same parts.

Reference numeral 10 represents the smoke house divided into a lower compartment 11 on the ground floor and an upper compartment 12 on the first floor.

On the ground floor is to be found a brick oven 13 reaching nearly up to the ceiling 14 forming the floor of the upper compartment. A smoke stack 15 is provided for the oven 13, extending upwardly through the upper floor and the roof to carry the excessive smoke from the oven 13 into the air. Positioned in the smoke stack 15 is a damper 16 with an operating handle 17 extending into the upper chamber 12 above the floor thereof.

Within the brick oven 13, standing on the cement or concrete floor 18, is placed a plate cylinder 19 constituting the fireplace closed on all sides, having a solid top and solid plate walls with the exception of vents 20, consisting of narrow slits, four being shown, placed a short distance below the top.

A fuel door 21 for the fireplace within the cylinder is provided on the outside of the brick oven. The door opening connects with the fireplace cylinder by means of a drum 22 and directly below the same is shown a draft regulating tube 23 with a damper 24 manipulated from the outside of the brick oven, see Figure 1.

At 25 is shown a flue pipe or hood for conveying the hot smoke from the oven 13 to the upper compartment 12. The smoke outlet from the hood is provided with a flap or damper 26 for regulating the flow of smoke, or entirely stopping

2

it from entering into the upper compartment 12. Within said upper compartment is formed the actual smoke room 27 by providing partitions 28 reaching down from the ceiling to within a short distance of the floor 14 to permit the smoke to pass from the outer part of the compartment into the smoke room 27 beneath its bottom edges.

In the upper compartment 12, beneath the bottom of the partitions 28, are provided steam pipes or coils 29 around the walls of the compartment 12, which are intended to still further increase the heat of the surrounding smoke passing from the hood 25 into the actual smoke room 27.

15 To insure the uniform heating and spreading of the smoke to all parts of the smoke room 27 electric or other fans 30 are provided around the walls of the room and on the outer wall of the compartment 12 another fan 31 is indicated for 20 the purpose of exhausting slowly all smoke from the smoke room 27 when required, and including the entire compartment 12.

Although only one smoke room 27 and one upper smoke compartment 12 have been shown, 25 it will be evident that one oven may be able to furnish hot smoke for several smoke rooms built around the chimney on the upper floor.

As a general rule the upper compartment 12 has a volume 40 or more times greater than the 30 brick oven 13. The height of the upper compartment need not be more than six or seven feet between floor and ceiling and about thirty feet long.

The articles to be smoked are placed in the 35 smoke room, either on shelves or stringed up in the case of herring or other fish on wires or slender wooden or metal sticks or on wire flakes in racks and suspended across the smoke room so that the hot smoke can circulate around them and between the several rows of the articles.

40 The method of operation is the following: The articles to be cured or smoked, such as herring or other fish, meat, sausage, ham, cheese etc., are deposited in a suitable manner in the 45 smoke room as already described.

A fire burning wood or other smoke producing fuel to produce dense smoke is thereupon lit in the fireplace within the steel cylinder 19. As the fire flares up a considerable amount of ashes, 50 embers, sparks and cinders will mingle with the rising smoke, and which, under ordinary circumstances, would come in direct contact with the fish, etc., in the smoke room. Aside from being a protection from fire, the fire chamber or cylinder 19 now prevents the undesirable ingredients

from leaving the cylinder, which is closed on all sides, whereupon they will strike the solid top and adhere thereto or to the walls of the cylinder or fall back to mingle with the combustibles. In this manner a much cleaner, more appetizing and more wholesome smoked article will be the result, because now the surface thereof will be free from such contamination. If cinders and ashes, etc., were permitted to remain in the smoke, they would collect and adhere to the moist skin or surface of the article making it not only unappetizing but also unsanitary as food.

By means of the present method and apparatus, all such contaminations are removed from the smoke produced within the firebox or cylinder 19 so that clean and refined smoke will now seep slowly through the vents 20, of the cylinder, the draft damper 24 therein being adjusted to regulate the burning and rate at which the thick smoke emanates from the vents 20 to collect in the surrounding space in the brick oven 13.

The damper 16, which was opened at first and has remained open in the chimney 15 to give the fire a good start, is now closed when the smoke has become of the desired density, and the damper 26, which up until now has remained closed, is automatically opened to permit the smoke from the oven 13 to rise through the flue in hood 25 to spread in all directions to fill the upper compartment 12 and the actual smoke room 27 within the same and where the fish or other articles for smoking are already deposited. The thick but clean smoke in said upper compartment further heated by the steam pipes 29 in order that the smoke may reach all parts within the smoke room 27, and particularly the fish, etc., when the fans 30 are started.

Finally when the smoking is concluded, the chimney draft is again opened and the fan 31 started to suck out all the smoke from the smoke room and other chambers.

It is to be understood that the invention as here disclosed is not limited to the details here described and shown but that the same may be varied widely without departing from the spirit of the invention as defined by the subjoined claims.

Having described the invention, what is claimed as new is:

1. A smoke house for curing food stuffs of any description and more particularly herring and other fish, comprising an oven having heat retaining brick walls, a closed-in fireplace consisting of a metal cylinder closed on all sides within the oven and so positioned that free space is provided all around the same in the oven, the metal walls of the fireplace having narrow vents adjacent the top thereof for permitting smoke to escape into said free space and compelling contaminating particles in the smoke to separate therefrom and collect above the vents, means for regulating the draft in the fireplace, a smoke room above said oven, an outer chamber around the smoke room in which said smoke room is suspended, said smoke room having an open bottom, a smokestack communicating with said oven and extending through said chamber, means for directing the smoke into the atmosphere and means in said stack for directing the smoke in said stack into said outer chamber, the smoke passing from the outer chamber into the smoke room through said open bottom.

2. A smoke house for curing food stuffs of any description and more particularly herring and

other fish, comprising an oven having heat retaining brick walls, a closed-in fireplace consisting of a metal cylinder closed on all sides within the oven and so positioned that free space is provided all around the same in the oven the metal walls of the fireplace having narrow vents below the top thereof for permitting smoke to escape into said free space and compelling contaminating particles in the smoke to separate therefrom and collect above the vents, means for regulating the draft in the fireplace, a smoke room above said oven, an outer chamber around the smoke room in which said smoke room is suspended, said smoke room having an open bottom, a smoke stack communicating with said oven and extending through said chamber, means in said stack directing the smoke to the atmosphere, means in said stack for directing the smoke into said outer chamber, the smoke passing from the outer chamber into the smoke room through said open bottom and additional means for forcing the smoke onto the foodstuff.

3. A smoke house for curing foodstuffs of any description and more particularly herring and other fish, comprising a brick oven with heat retaining walls, a closed-in fireplace consisting of a metal cylinder closed on all sides within the oven and so positioned that free space is provided all around the same in the oven, the walls of the fireplace having vents adjacent the top thereof for permitting smoke to escape into said free space and compelling contaminating particles in the smoke to separate therefrom and collect above the vents, means for regulating the draft in the fireplace, a smoke room above said oven, an outer chamber having heat retaining walls around the smoke room, said smoke room having an open bottom and suspended in said chamber, a smokestack communicating with said oven and extending through said chamber, means for selectively directing the smoke to the atmosphere or into said outer chamber, means for circulating the smoke and maintaining its heat within said smoke room, the smoke passing between the outer chamber and the smoke room through said open bottom.

4. A smoke-house comprising an oven, a closed-in fireplace within said oven and spaced from the walls and top of said oven, outlet means adjacent the top of said fireplace for conducting smoke between said walls of said oven and fireplace, means for regulating the draft in said fireplace, a chamber above said oven, a smoke room having the bottom open suspended in said chamber, a smoke-stack extending from said oven through said chamber, selectively operable means in said stack for directing smoke from said oven to said chamber and said smoke room or through said stack.

5. A smoke-house comprising an oven, a closed-in fireplace within said oven and spaced from the walls and top of said oven, outlet means adjacent the top of said fireplace for conducting smoke between said walls of said oven and fireplace, means for regulating the draft in said fireplace, a chamber above said oven, a smoke room having the bottom open suspended in said chamber, a smoke-stack extending from said oven through said chamber, selectively operable means in said stack for directing smoke from said oven to said chamber and said smoke room or through said stack, said last-mentioned means including a port in said smoke-stack, damper means covering said port and a valve in said stack.

6. A smoke-house comprising an oven, a closed-in fireplace within said oven and spaced from the

walls and top of said oven, outlet means adjacent the top of said fireplace for conducting smoke between said walls of said oven and fireplace, means for regulating the draft in said fireplace, a chamber above said oven, a smoke room having the bottom open suspended in said chamber, a smoke-stack extending from said oven through said chamber, selectively operable means in said stack for directing smoke from said oven to said chamber and said smoke room or through said stack, said last-mentioned means including a port in said smoke-stack, damper means covering said port and a valve in said stack, and heating means in said chamber for conditioning the smoke therein.
